UNITED STATES PATENT OFFICE.

WALTER V. TURNER, OF EDGEWOOD, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

FLUID-PRESSURE BRAKE.

1,108,947.

Specification of Letters Patent. Patented Sept. 1, 1914.

Application filed January 7, 1909. Serial No. 471,134.

To all whom it may concern:

Be it known that I, WALTER V. TURNER, a citizen of the United States, residing at Edgewood, in the county of Allegheny and 5 State of Pennsylvania, have invented new and useful Improvements in Fluid-Pressure Brakes, of which the following is a specification.

This invention relates to fluid pressure 10 brakes, and more particularly to the engineer's brake valve, or means for controlling the admission and release of fluid under pressure to and from the train brake pipe.

With the constantly increasing length of 15 trains operated in railway service, it has become necessary to employ a more tightly fitting equalizing piston than formerly in connection with the brake valve in order to prevent leakage around the piston as 20 much as possible, as this leakage tends to equalize the opposing pressures on the piston and thereby keep the discharge valve from seating, so that a greater than desired reduction in train pipe pressure is produced. 25 It has been found, however, that in some cases where tight fitting pistons are employed, when it is desired to make a second application of the brakes immediately following a first application, for example, as 30 in making a two application stop in railway passenger service, an excess of pressure over 35 that in the train pipe sometimes occurs on the equalizing reservoir side of the piston, due to the movement of the brake valve first 40 to full release position after making the primary application of the brakes and then to lap position, in which the higher pressure in the equalizing reservoir cannot equalize with the train pipe pressure on account of 45 the tight equalizing piston and so, the pressure in the train pipe equalizing throughout the length thereof as heretofore, quite a difference may exist between the pressures in 50 the equalizing reservoir and train pipe such that when the second application of the brakes is attempted, there is liable to be no further reduction in train pipe pressure or at least not to the degree contemplated by the engineer, as the movement of the brake valve may only serve to reduce 55 the higher pressure in the equalizing reservoir to the normal train pipe pressure.

The principal object of my present invention is therefore to provide means for

automatically relieving any excess pressure 55 occurring on the equalizing piston.

In the accompanying drawing, the single figure is a side elevation, partly in section, of a brake valve embodying my improvement. 60

The brake valve illustrated in the drawing comprises a casing 1 containing the usual rotary valve, the operation of which is effected by the brake valve handle 2. An equalizing piston 3 forms a movable partition between chamber 4 above the piston and open to an equalizing reservoir in the usual manner and a chamber 5 on the opposite side of the piston which is open to the train pipe, and said piston is adapted to 70 operate an equalizing discharge valve 6 for controlling the exhaust of air from the train pipe to the atmosphere.

As so far described the brake valve is of the usual construction, and as well known, 75 the chamber 4 above the piston 3 is adapted to charge up with the train pipe in the running and release positions of the brake valve. When the brakes are to be applied, the handle 2 is moved to service application 80 position in which air is discharged from the chamber 4 to the atmosphere, the handle being moved back to lap position when the desired reduction in pressure is obtained. The higher train pipe pressure in chamber 85 5 then forces the piston upward and unseats the discharge valve 6. Air thereupon flows from the train pipe to the atmosphere and continues to flow until the train pipe pressure is reduced to slightly less than the pressure 90 in the chamber 4, when the preponderating pressure in chamber 4 forces the piston 3 downwardly and closes the discharge valve 6.

According to my improvement, the equalizing piston is constructed so as to permit of 95 a farther downward movement thereof beyond the normal closed position in which extreme position communication is opened around the piston through one or more 100 equalizing grooves 7. In order to permit this relative movement of the piston, the discharge valve 6 is made movable with respect to the piston, preferably being mounted in a chamber 8 in the equalizing piston 3 and is 105 yieldingly maintained in its normal relative position by means of a coil spring 9, a shoulder 11 being provided on the stem 10 of the

valve, so as to determine or limit the outward movement of the valve.

In the normal position of the parts, as shown in the drawing, the piston 3 forms a tight joint between the chambers 4 and 5, on its opposite sides, with the discharge valve 6 closed, and the operation is the same as with the ordinary equalizing discharge valve, but should the pressure above the piston in chamber 4 exceed the train pipe pressure below the piston, then it will be seen that the piston 3 is moved downwardly beyond its normal position, while the discharge valve 6 remains seated, and communication is opened around the piston through the grooves 7. Air then flows from the chamber 4 and the equalizing reservoir through said grooves to the train pipe until substantial equalization of pressures is attained; when the piston 3 is automatically returned to its normal position by the action of the spring 9, closing the grooves 7. It will now be apparent that I have provided a simple means whereby any excess of pressure occurring above the equalizing piston is automatically relieved.

Having now described my invention, what I claim as new and desire to secure by Letters Patent, is:—

30 1. In a brake valve, the combination with means for supplying fluid to the train pipe for releasing the brakes, a movable abutment subject to the opposing pressures of the train pipe and a chamber and independent of 35 said means and valve means operated by said abutment for controlling the discharge of air from the train pipe, of a restricted port opened by an excess of fluid pressure on the chamber side of said abutment for equalizing the fluid pressures on opposite sides of 40 said abutment.

2. In a brake valve, the combination with a movable abutment subject to the opposing pressures of the train pipe and a chamber,

valve means operated by said abutment for 45 controlling the discharge of air from the train pipe and means separate from said abutment for supplying fluid to the train pipe, of restricted ports controlled by the movement of said abutment and adapted to 50 be opened by an excess of fluid pressure on the chamber side of said abutment to permit the fluid pressures on opposite sides of the abutment to equalize.

3. In a brake valve of the usual type having a direct passage through which fluid is supplied to the train pipe, the combination with an equalizing discharge valve mechanism comprising a piston subject to the opposing pressures of the train pipe and a 60 chamber, a valve operated thereby for controlling the discharge of air from the train pipe, and restricted ports adapted to be opened by the movement of said piston under an excess of pressure in said chamber 65 for permitting the equalization of fluid pressures upon opposite sides of said piston.

4. In a brake valve of the usual type having a direct passage through which fluid is supplied to the train pipe in running and 70 release positions, the combination with an equalizing discharge valve mechanism comprising a piston subject to the opposing pressures of the train pipe and a chamber, a valve operated thereby for controlling the 75 discharge of air from the train pipe, and restricted ports adapted to be opened by the movement of said piston under an excess of pressure in said chamber for permitting the equalization of fluid pressures upon opposite 80 sides of said piston.

In testimony whereof I have hereunto set my hand.

WALTER V. TURNER.
